SUNDAE OR THE LIKE

Fred L. Meagher, Blairstown, N.J., assignor to American
Can Company, New York, N.Y., a corporation of
New Jersey

Filed Feb. 6, 1958, Ser. No. 49,517

Term of patent 14 years

(Cl. D82—2)

Fig. 1.

Fig. 2.

Fig. 3.

Fig. 4.

Fig. 1 is a top plan view of a stylized representation of a sundae showing my new design;

Fig. 2 is an elevational view thereof, partially in section;

Fig. 3 is a top plan view of a photographic representation thereof; and

Fig. 4 is a perspective view thereof.

The candies have been omitted from Figs. 1 and 2 for convenience of illustration.

I claim:

The ornamental design for a sundae or the like, substantially as shown and described.
